UNITED STATES PATENT OFFICE.

ARNET P. BOSTON, OF EUREKA, TEXAS.

DRAG-SAW.

SPECIFICATION forming part of Letters Patent No. 329,531, dated November 3, 1885.

Application filed July 20, 1885. Serial No. 172,130. (No model.)

To all whom it may concern:

Be it known that I, ARNET P. BOSTON, a citizen of the United States, residing at Eureka, in the county of Navarro and State of Texas, have invented certain new and useful Improvements in Drag-Saws; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in drag-saws; and it consists in certain novel features of construction, combination, and arrangement hereinafter fully described, and specifically pointed out in the claim.

In the drawings, Figure 1 is a side elevation of a drag-saw provided with my improvements, and Figs. 2 and 3 are detail views of the mechanism for feeding the saw to the work. Fig. 4 is a detail end view of the driving mechanism. Fig. 5 is an enlarged plan view of the cross-piece connecting the upper ends of the slotted guide-standards.

A is a standard bifurcated at its upper end, the bifurcation extending about two-thirds of the way down the standard. The standard is provided with a suitable rest or base-piece, A', by which it is held upright upon the ground. Beams B are secured to the standard A, on each side of the same, and secured by the braces C. The braces C are provided with handles C', by which the machine may be moved from place to place. A crank-shaft, D, is journaled in suitable bearings on the two arms of the bifurcated portion of the standard A, the crank being between the said arms. One end of the crank - shaft is provided with a pinion, E, which meshes with a drive gear-wheel, E', operated by a crank-handle, E'', as shown. A pitman is connected at one end to the crank-shaft D, and is driven by it in the operation of the device. The other end of the pitman is connected to the saw G and the lower end of the pendulum, as shown. The saw works between the ends of the beams, which are held to the log by a pin in the usual manner. The upper end of the pendulum H is pivoted within a notched head-block, I, as clearly shown in

Fig. 3. This block slides in the slotted standards J J, which are secured in mortises in the beams B. The head-block I is provided with a rack-bar, I', which is extended upward from the said block and forms part of the same. A pawl, I'', engages the rack-bar I' and prevents the backward movement of the same. The standards J J are connected at their upper ends by a cross-piece, J', which is provided with an opening, J'', through which the rack-bar I' projects. A pulley, J'', is supported in the cross-piece, which is provided with a suitable opening for the proper working of the same. A cord, K, attached to the head-block I, passes over the pulley J'' and back to a shifting - spool, L, supported between the upper ends of the bifurcated standard A. The spool L is rigidly secured to a shaft, L', which is provided at one end with a knob, L'', as shown. The shaft L' is loosely supported in suitable openings formed in the arms of the standard A, and is shifted through the same during the operation of the device. The spool L is provided with a projection on one end, which engages pins on the standard to prevent the rotation of the spool. Between the opposite end of the spool and the arm of the standard I place a coiled spring around the shaft L', which serves to keep the spool in engagement with the pins on the standard.

In operation motion is given the saw by turning the drive-wheel E', and the motion thus created will be transmitted to the saw through the pinion E, crank-shaft D, and pitman F, the crank-shaft and pitman changing the circular motion to reciprocating. The pendulum H will be caused to oscillate, and will serve to give a smooth regular motion to the saw. As the cut in the log is deepened, the spool L can be turned, letting out the cord K and allowing the head-block I to fall, and the saw will be thus kept to the work. The rack-bar and pawl prevent the tension of the cord drawing the head-block backward.

To operate the spool, the knob L'' is pushed inward, releasing the projection on the spool from engagement with the pin on the standard, and then rotated. By releasing the hold on the knob the coil-spring on the shaft L' will push the spool toward the opposite arm of the standard and re-engage the pins and projection.

Having thus described my invention, what I claim, and desire to secure by Letters Patent, is—

The herein-described drag-saw, consisting of a standard, two beams connected to the standard on opposite sides thereof, a crank-shaft held by the standard, suitable drive-gearing for operating the same, a pitman connecting the crank-shaft and the saw, a pendulum attached to the saw and the pitman at one end and to a sliding head-block at the other end, the head-block sliding in the slotted standards and having a rack-bar extended therefrom, a pawl engaging the rack, the operating-cord attached to the head-block and passing over a

guide-pulley on the slotted standards and around a spool rigidly secured to a laterally-movable shaft, a projection on one end of the spool to engage a pin on the standard, and a spring coiled around the shaft and bearing upon the opposite end of the spool and an arm of the standard, as and for the purposes set forth. 20

In testimony whereof I affix my signature in presence of two witnesses.
